UNITED STATES PATENT OFFICE.

WILLIAM EDW. COMPO, OF TOLEDO, OHIO.

FLASH-LIGHT.

1,110,110.

Specification of Letters Patent.

Patented Sept. 8, 1914.

Application filed February 19, 1914. Serial No. 819,730.

To all whom it may concern:

Be it known that I, WILLIAM E. COMPO, a citizen of the United States, and a resident of Toledo, in the county of Lucas and State of Ohio, have invented an Improvement in Flash-Lights, of which the following is a specification.

My present invention relates to electric flash lights, and one of the principal objects thereof is to provide a flash light which may be used with the standard sized dry cells.

Another object of the invention is to provide a light of the class described, which may quickly and easily be attached to or removed from a dry cell, and which may be adjusted when in place thereon in positions where flash or steady light may be obtained.

A further object of the invention is to provide a device of the class described, which will be simple, durable, efficient in operation and inexpensive to manufacture.

With these and other objects in view, which will become apparent as the description proceeds, the invention resides in the construction, combination and arrangement of parts as will be hereinafter fully described and claimed, and illustrated in the accompanying drawing, in which like characters of reference indicate like parts throughout the figures, of which—

Figure 1 represents a perspective view of the invention as applied to a dry cell of standard construction. Fig. 2 represents a vertical sectional view through the same. Fig. 3 represents a horizontal sectional view through the device taken on the plane indicated by the line 3—3 of Fig. 2. Fig. 4 represents a side elevational view of the spring means for adjusting the contact between the bulb and the positive pole of the battery.

Referring more particularly to the drawing: 5 indicates a dry battery of standard size and construction, whose carbon or positive pole is indicated at 6, and whose negative pole 7 consists of the usual binding post.

The invention comprises an attachment which may be positioned on the battery, including a cylindrical body portion 8 open at one end, and having its opposite end inwardly flanged as at 9 to provide a seat for a concave-convex reflector 10 which is positioned within the body member 8, and whose edge is outwardly flanged as at 10 to rest against flange 9. A double convex lens 11 rests at its edge upon flange 10, and said lens and reflector are maintained in position by

means of a collar 12 provided with an inwardly turned flange 13 embracing the edge of the lens, said collar being threaded onto the end of tube 8 adjacent flange 9. The concavity or curvature of the flanges 10 and 13, conform to the curvature of lens 11 at its edge, so that the lens is snugly seated in place.

The reflector 10 is provided at its central portion with a threaded neck 14 projecting outwardly with respect to the reflector, and positioned within neck 14, is shank 15 of an electric light bulb 16. The shank projects slightly beyond neck 14, and is provided with the usual contact point 18. A second contact point is provided, which comprises a metallic stud 19, having an enlarged flat head 20, against which a flanged insulating sleeve 21 rests, said sleeve being supported by the shank of the stud, and against the sleeve at the opposite side thereof from head 20, rests an insulating collar 22, and surrounding said sleeve between collar 22 and the flange on the sleeve, is one end of a coil spring 23, the opposite end of which is adapted to thread onto the outer surface of the threaded neck 14. The function of spring 23, is to maintain points 18 and 20 in constant contact.

Positioned on stud 19 between the collar 22 and a nut or head 24, is one end of a second coil spring 25, the opposite end of which is adapted when the device is positioned on the dry cell to contact with the carbon pole 6 of the cell, thus setting up the positive branch of an electric circuit between the lamp and the battery through the positive pole 6, spring 25, stud 19, and contacts 20 and 18.

The inside diameter of tube 8, is substantially equal to or slightly larger than the outside diameter of the dry cell, and as clearly illustrated, the tube is adapted to be slipped over the cell so that the spring 25 will contact with the positive pole 6, and in order to maintain the tube in place, the same is provided near the end opposite the lamp with an inwardly directed annular bead 26, and is further provided with a plurality of inwardly stamped lugs 27 adapted to coact with bead 26 in holding the tube firmly in place on the cell. The tube is provided on one side with a spring tab 28 stamped outwardly from the tube, and adapted to overlie the negative pole 7 of the cell in spaced relation thereto. By

pressing with the thumb or finger on tab 28 until the same comes in contact with pole 7, the circuit is completed from the lamp through the stem 15, neck 14, metal reflector 10, and the metal tube 8, tab 28 and through the negative pole back to the battery whereupon the lamp will be lighted, and will remain lighted so long as the tab is in contact with the negative pole, but upon release of pressure from the tab, the same will immediately spring away from pole 7, thus breaking the circuit and extinguishing the light.

The negative poles of dry cells, are ordinarily placed as illustrated, on the rim of the metallic casing forming a portion of the cell and they project slightly beyond the outer surface of the cell, and therefore it is evident that upon rotating the tube 8 relative to the battery, in either direction from the position in which it is illustrated, that a portion of the edge of opening 29 formed by the stamped tab 28 will come in contact with pole 7, and thus the circuit will be completed through the lamp, and the same will be ignited and remain in that state so long as the tube is in contact with pole 7. By this arrangement it is evident that the user may position the tube so that a flash light may be secured at will, or a constant light be obtained, according to whether the tube is positioned so that the tab may be pressed in contact with pole 7 at will, or adjusted so that a portion of the tube will come in contact with the pole.

Although I have described the preferred embodiment of my invention, I may desire to make such changes in the construction, combination and arrangement of the parts thereof, as do not depart from the spirit of the invention and the scope of the appended claims.

I claim:

1. A device of the class described comprising a metal tube adapted to be positioned on a standard sized dry cell, a metal reflector carried by said tube, a lens carried by the tube and positioned over the reflector, a threaded sleeve carried by the reflector, an electric light bulb having its shank threaded into said sleeve and extending beyond the same, a coiled spring threaded at one end onto said sleeve, a metal stud carried by the opposite end to said coiled spring, insulating material positioned between said spring and stud, said spring adapted to maintain one end of said stud in contact with the contact on the bulb shank, a second coiled spring carried by said stud, and in contact therewith, said second spring being insulated from the first spring, said second spring when said tube is positioned on a dry cell, adapted to contact with the positive pole of the battery, a spring tab punched from said tube, and leaving an opening therein, said tube adapted to be positioned on a cell so that the

negative pole of the cell is brought into said opening, in position to be contacted by said tab when pressure is put upon the latter, said tube provided with a bend and lugs for maintaining the same in position on the cell, 70 said tube adapted to be rotated relative to said cell to bring one edge of said opening in contact with said negative pole for maintaining a steady light.

2. A device of the class described comprising a metallic tube, a reflector carried thereby, a lens carried by said tube above the reflector, a threaded neck carried by said reflector, an electric light bulb having a shank positioned in said neck, a spring threaded at 80 one end onto said neck, a metal stud carried by the opposite end of said spring, said stud being insulated from said spring, a second spring carried by said stud, in contact therewith but insulated from first said 85 spring, a spring tab stamped from said tube, and means for positioning said tube on a dry cell.

3. The combination with a standard sized dry cell, of a bulb, a tube supporting said bulb, means for detachably securing said tube on the cell, means for throwing said bulb at will into circuit with said cell when the tube is in one position with relation to the cell, said tube being adjusted with relation to the cell, and means for throwing said bulb into contact circuit with said cell when said tube is shifted into another position.

4. A device of the class described including a dry cell, an electric light bulb movable 100 relatively to the cell, means for constantly maintaining electrical communication between one pole of the bulb and cell, and means for establishing electrical communication between the other pole of the bulb 105 and cell at will when the bulb is in one position relative to the cell, and constantly when the bulb is in another position relative to the cell.

5. A device of the class described including 110 a cell, an electric light bulb movable relatively to said cell, a support for the bulb, means for establishing electrical communication between the light support and one pole of the cell, said bulb being in communication with its support, and means for maintaining constant electrical communication between the other pole of the light and cell irrespective of the position of the light relative to the cell, said means including a metallic stud having a head at one end, an insulating sleeve surrounding said stud and having an insulating flange abutting the stud head, a spring engaging said insulating sleeve at one end and said bulb support at 120 the other end, for maintaining the stud head in contact with said other pole of the bulb, an insulating collar on said stud, a head on said stud, opposite the headed end thereof, and a spring having one end connected with 125

the stud between said insulating collar and last said head, the opposite end of said spring contacting with the said other pole of the cell.

5 6. A device of the class described comprising a metallic tube adapted to be positioned on a dry cell, an electric light bulb in electrical communication with and supported by said tube, means for adjustably positioning the tube on the cell, means for establishing constant electrical communication between the inner pole of the bulb and the inner pole of the cell irrespective of the movement of the tube relatively to the cell, 10 said tube being provided with an opening adapted to be brought into registration with the outer pole of the cell, a tab overhanging the opening, said tab adapted to be moved into engagement with the outer cell pole at

will for producing flash light, said tube 20 adapted to be moved whereby to engage the outer cell pole at one edge of the opening for producing constant light.

7. A device of the class described comprising a dry cell having a pole at its outer side, 25 a tube having an open end adapted to be positioned on the cell, an electric lamp at the other end of the tube, the tube being provided with means for establishing electrical communication at will with the outer pole of 30 the cell when the bulb is in one position relatively to the cell and constantly when the bulb is in another position.
